United States Patent Office.

WILLIAM C. BANKS, OF COMO DEPOT, MISSISSIPPI.

Letters Patent No. 65,865, dated June 18, 1867.

IMPROVEMENT IN COTTON-PRESSES.

The Schedule referred to in these Letters Patent and making part of the same.

TO ALL WHOM IT MAY CONCERN:

Be it known that I, WILLIAM C. BANKS, of Como Depot, in the county of Panola, and State of Mississippi, have invented certain new and useful Improvements in Cotton-Presses, for baling cotton; and I do hereby declare the following to be a full, clear, and exact description of the construction and operation of the same, reference being had to the accompanying drawings, making a part of this specification, in which—

Figure 1 represents a top plan of the press, with the head in its working position, in black lines, and as swung out of the way, when filling the press with cotton, in blue lines.

Figure 2 represents a vertical cross-section through the press.

Similar letters of reference, where they occur in the separate figures, denote like parts of the press in both of the drawings.

My invention relates more especially to the manner in which I arrange the screw-head and its several appliances, so that the screw, platen, and head may be swung to one side, to facilitate the filling of the pressing-box with cotton, and then brought back over the said box, so that the platen or follower may be run down upon the cotton, to press it compactly into a bale.

To enable others skilled in the art to make and use my invention, I will proceed to describe the same with reference to the drawings.

A represents a stout, substantial frame, of rectangular form, having a bed or base, B, suitably secured thereto, and strong enough to resist the pressure put upon the cotton that lies upon it. On, above, or around this base or bed there are side doors, c, and end pieces, to form a chamber, in which the cotton is pressed into compact form, and in which it may be baled in any of the common, well-known ways, the doors being swung open, and the end pieces released for the easy removal of the pressed bale. Above this pressing or baling-chamber, and forming a continuation of it, is the filling-in chamber D, the sides and ends of which may be permanently attached to each other, or to the frame A, or both. This chamber D is designed for receiving the loose cotton that is afterwards to be pressed into the bale. To the top cross-pieces of the frame A is pivoted (as at a) one end of the cross-head or beam, E, the other end thereof being supported in a metallic piece or frame, F, in a slot, b, in which said free end of the cross-head or beam E may move and be guided as it swings on its pivot a. Through this cross-head or beam E, and through a nut or female screw therein, the screw-shaft G passes and works, said screw-shaft having upon its lower end a platen, H, that nearly or quite touches the sides and ends of the chambers in which it moves. To the top of the screw-shaft G there is secured a beam, I, and to the beam I, and to each other, two sweep-levers, J J, by which the screw-shaft is turned. To swing the cross-head or beam E, and its appendages and appliances, out from its working position in the chambers, so as to leave a clear and unencumbered space, to fill in the loose cotton, I arrange as follows: A windlass, K, is attached to one side of the press, which may be turned by a crank, L. To this windlass is fastened one end of a rope or chain, c, the other end thereof being first passed over a pulley, d, in the outer end of the frame F, and then fastened, at e, to the cross-head or beam E. To the opposite side of the cross-head or beam E there is fastened another rope or chain, f, which, after passing over a pulley, g, passes down, and is fastened by its other end to the windlass at h; so that when the cross-head, screw, platen, and other connected parts are swung out, by the winding up of the rope or chain c on the windlass k, the other rope or chain f is unwound; and when the chambers are filled with cotton, by reversing the motion of the windlass the several parts are returned over said chamber, and ready to commence the pressing of the cotton, the rope or chain f, in this case, winding up on the windlass, and the other, c, unwinding. The frame F is so extended and curved that the cross-head E, when swung round out of the way, will continue to be supported in it, said head having a friction-roller, i, connected to it, which runs through the slot b, and thus causes the head to move easily back and forth.

Having thus fully described my invention, what I claim therein as new, and desire to secure by Letters Patent, is—

In combination with a cotton-press, substantially such as described, the pivoting, at one end, of the beam that carries the screw-plates and sweeps, and the curved guide or frame F, and windlass and cords, or their equivalents, for moving said beam, substantially as and for the purpose herein described and represented.

WM. C. BANKS.
